INKING DEVICE FOR MIMEOGRAPH MACHINES

Humberto L. Bueno, New York, N. Y.

Application November 24, 1933, Serial No. 699,539

13 Claims. (Cl. 101—120)

The present invention relates to mimeograph machines and more particularly to an improved inking device for such machines.

In the use of mimeograph machines, it has been necessary to supply the stencil with ink. Generally, an ink pad has been provided over the outer surface of a perforated metal drum and under the inner surface of the stencil. The pad was adapted to absorb a certain quantity of ink and to redistribute it to the stencil. The ink was usually applied to the pad by means of a manually operated brush which was mounted on the inking device located on the inside of a mimeograph drum. In the use of such prior devices, the first copies were printed quite heavy after inking, and then as the run proceeded, the prints would become lighter and lighter until finally they became too faint for practical purposes. It was then necessary to stop the machine and reink the pad by manually operating the inking device. Furthermore, there was a tendency toward non-uniformity of printing due to the difficulty of inking the pad evenly and due to the difficulty of maintaining such pad in a uniformly inked condition. In applying ink to a pad by means of the prior inking device, considerable skill and experience was required to determine the spots requiring ink and the correct quantity of ink and also to insure not only the even distribution throughout the pad or stencil but also to prevent smudging and to avoid faint prints. Moreover, a great deal of time was lost in stopping the machine and reinking, especially when attempts were made to produce inked copies which were anything like uniform. Then again, no means were provided to apply a definite and correct amount of ink which was commensurate with the amount of work being done. Prior inking devices had the foregoing as well as other serious disadvantages. Although many attempts have been made to overcome the aforesaid disadvantages, none, as far as I am aware, has been completely satisfactory and wholly successful in practical use.

It is an object of the present invention to provide a mimeograph machine inking device which is capable of feeding ink and of spreading such ink evenly and uniformly over the entire surface of the drum, pad, or stencil, whereby uniformly and properly inked mimeograph copies can be made from the start to the end of the run.

It is another object of the present invention to provide an inking device for a mimeograph machine which functions practically automatically while the machine is operating and which will

enable such machine to print uniformly inked work continuously throughout a run in which the last copies are substantially as heavily and uniformly inked as the first sheets.

It is still another object of the present invention to provide an automatic inker for a mimeograph machine which will make it possible for such a machine to produce neater and more uniform work in less time than heretofore.

It is a further object of the present invention to provide an automatic inking device which will feed the correct amount of ink commensurate with the amount of work being done and which will cease functioning when the machine stops.

Another object of the invention is to provide an inking device having adjustable supports which will afford long wear to the device and which will enable the same to operate smoothly and with minimum friction throughout its life.

It is also within the contemplation of the invention to provide an inking device which is simple in design, easy to install, and economical to manufacture and which may be added to or substituted for the present means of inking mimeograph machines without entailing substantial changes.

Other objects and advantages of the invention will become apparent from the following description, taken in conjunction with the drawings, in which:

Fig. 1 is an end elevation view, partly fragmentary, of an inking device embodying my invention as incorporated in a mimeograph machine;

Fig. 2 illustrates a side elevation view of the present inking device;

Fig. 3 depicts a top plan view of the inking device shown in Figs. 1 and 2; and

Fig. 4 is a side elevation view, partly fragmentary and partly in section, of a modified embodiment of the invention.

Referring more particularly to Fig. 1, the reference character 1 designates a drum of a mimeograph machine having a perforated surface 2 covering the inking region thereof. Fastened to the outside of the drum may be a pad or other absorbent substance 3 over which the stencil is fitted in the usual manner. Gutters 4 may be provided on the inside of drum which prevent any stray ink from flowing down the end plate 5 of the drum which might tend to dirty the machine and interfere with the lubrication of the same. The gutters 6 and 7 extending longitudinally across the drum at the extremities of the inking

surface 2 likewise serve to prevent the overflow of ink. It will be seen that the gutters 6 and 7 also serve as stops the function of which will be explained more fully hereinafter. The end plates 5 each have an aperture 8 for an axle 9 which may be held in position by any suitable arrangement, such as bushings 10.

Suspended from the axle by means of supports 11 and bearings 12, is an ink reservoir 13 which 10 may be cylindrical in shape, which extends throughout the width of the drum, and which is free to rotate around the axle. Annular bearings 12 are mounted on the axle and may have set screws 14 which may be adjusted to provide the 15 proper amount of braking action as the reservoir swings around the axle. In practice, it has been generally found unnecessary to provide the braking action. Each support 11 is adjustably screwed into the bearings and held in place by 20 lock nut 15. The lower end of the support adjustably fits into the outwardly projecting flange 16 on the reservoir and is secured in position by a lock nut 17 or some other suitable means. In 25 the event that it is desired to maintain the reservoir in a central position on the axle, two springs 18 may be provided which hold the bearings 12 in spaced relation and prevent lateral shifting of the same.

Along the bottom of the reservoir, a plurality 30 of orifices 19 preferably of a capillary character are provided for automatically feeding the ink when the machine is in operation. It has been found that orifices having a diameter of about one millimeter and spaced apart approximately 35 1/2 inch gave satisfactory results. Of course, it is to be understood that a variation in the spacing and in the size of the orifices may be made depending upon the viscosity and type of ink and the quantity of feed necessary, as one skilled 40 in the art will readily understand.

On the top of the reservoir is an inlet port 20 which is preferably of a wide mouthed character to facilitate filling the reservoir with ink. It has been found advantageous to provide the port with 45 a close fitting hermetical seal 21 to prevent the leakage of air into or the leakage of ink from the reservoir. A hand operated air vent 22 is also located on the top of the reservoir and is adapted to admit air into the reservoir when 50 starting, as will be more fully described hereinafter. A screw cap 23 or other suitable device fits snugly over the vent to prevent the leakage of air and/or ink.

An annular replaceable brush holder 24 having 55 an open bottom fits over the reservoir and is fastened thereto by means of screws 25. The lower edges of the holder are provided with flaring flanges 26 and 27 which act as brush and splash guards. A bristle brush 28 projects downwardly 60 from the holder into which it is seated and presents practically a single bristle surface 29 to the drum. The brush is adapted to receive the ink as it drips from the capillary orifices and then to distribute it evenly as a substantially uniform 65 film over the inner surface of the perforated diaphragm of the drum.

As may be clearly seen from Fig. 1, the reservoir hangs downwardly in its normal position like a pendulum. The vertical position of the 70 reservoir has been designated for convenience' sake as being 180° clockwise from the top of the drum. Two stops 6 and 7, hereinbefore referred to as gutters, project inwardly at about 90° and 315° respectively. When the drum re- 75 volves in a clockwise direction, the reservoir re-

mains in its normal position until stop 6 comes in contact with the splash guard 26 and pushes the suspended reservoir around to about the 5° position where the force of gravity acts upon the reservoir and makes it fall rapidly away from the stop 6. The pendulous reservoir will then swing around to about the 270° position at about which point the guard 27 will catch up with and be checked by the stop 7. The brush will then tend to come to rest at the 180° position until the stop 6 in its rotation again comes in contact with and pushes the guard 26 at which time the cycle begins anew. During each revolution of the drum, it will be observed that the brush sweeps over the entire stencil area of the drum twice, once in each direction. The ink is thus spread evenly and thoroughly throughout the ink region, thereby insuring for all parts a uniform and proper amount of ink. Furthermore, the mimeograph copies are uniformly dark in printing 20 throughout the run. In this manner, heavy prints at the beginning of the run and a gradual fading of the ink impressions as the run progresses until finally the prints become too faint for practical purposes, are obviated. Likewise, 25 smudging and blotchy work is eliminated.

When the ink reservoir is in its downward position a certain definite quantity of ink will feed through the orifices and drip onto the brushes. As the ink flows, a partial vacuum is created 30 within the reservoir which will prevent any more ink from feeding while the reservoir remains in its downward position. When the reservoir is revolved and is inverted to about the 0° position, air enters the orifices and dissipates the partial 35 vacuum. As the reservoir again returns to its downward position, a further definite quantity of ink will be released. In this manner, the correct amount of ink is continually liberated in direct proportion to the amount of work which 40 is being done. When the machine stops and the reservoir is at rest, the flow of ink is stopped by the creation of a partial vacuum. Thus, the copies 45 or machine do not become saturated and soiled with ink. The operation is practically automatic and continuous and obviates the necessity of stopping the machine for hand-inking or spreading the ink in conventional mimeograph machines. Furthermore, since the ink is continually being fed with each revolution of the 50 drum, there is no gradual fading of the copies or prints as the run progresses.

When starting the run or applying a fresh ink pad, it may be desired to supply a certain amount 55 of ink to properly saturate the stencil area including the pad and drum diaphragm. To accomplish the foregoing, air vent 22 may be opened to permit a sufficient quantity of ink to flow prior to actual running of the machine. When enough ink has been administered to the stencil 60 area, the air vent is tightly closed and the normal operation begun.

When the machine is not in operation for any 65 length of time, as a safety measure, it has been found desirable to crank the drum around until the reservoir is in an inverted position. In this position, it is impossible for the ink to seep through the capillary orifices in the event that there is a small air leak in the reservoir or one of the ports.

A modified embodiment of the invention is 70 illustrated in Fig. 4. In this figure a drum 4 of a mimeograph machine has mounted on its central shaft 9 and suspended therefrom a triangular ink reservoir 30. In order to minimize the 75

friction between the shaft 9 and mountings 31, ball bearings 32 may be provided. Supports 33 are adjustably screwed into the bearings and locked thereto by means of a lock nut 34.

5 The ink reservoir has a laterally projecting flange 35 on each end which are threaded to receive the supports 33. Lock nuts 36 hold the supports firmly in position. Two sets of brushes 37, forming practically a single bristle surface 38, are replaceably mounted on the sides of the ink reservoir. A plurality of capillary orifices 39 at the lower apex of the reservoir feed the proper amount of ink onto the lower meshed portion of the brushes from where the ink is fed onto the stencil area. In this manner the ink is distributed evenly and uniformly throughout the bristle surface of the brush, and in turn throughout the entire surface of the drum, pad and stencil.

20 At the top of the ink reservoir is located a stoppered inlet port 40. It has been found desirable to offset the port from the center of the reservoir so as to facilitate the pouring of the ink. There is also located on the top of the reservoir a hand air vent 41 for use in starting as explained hereinbefore. It is preferable to provide air tight stoppers 42 and 43 for ports 40 and 41 respectively to prevent the leakage of air and ink which might tend to interfere with the normal inking of the machine.

25 On each side of the ink reservoir, covering the brushes, are splash guards 44 which are made of some resilient material to reduce the shock as the stops 6 and 7 come in contact therewith. The 30 operation of the modified embodiment is substantially the same as that described hereinbefore, and, consequently, it is believed to be unnecessary to repeat the description.

35 It is to be observed that the ink reservoir may be raised or lowered to such a position where the brushes will touch the metal drum sufficiently to spread the ink without creating too much pressure on the drum which might have a braking action to the pendulous motion. Likewise, 40 as the brush wears down, it is only necessary to lower it a small amount by adjusting supports 11 in order to restore the proper inking action of the brush. In this manner longevity of the brush is made possible.

45 50 Although the present invention has been described in connection with certain specific embodiments thereof, it is understood that variations and modifications may be resorted to without departing from the spirit of the present invention as defined in the appended claims.

55 I claim:—

1. An inking device for mimeograph machines comprising a pendulous ink reservoir suspended from the axle of the drum of a mimeograph machine, stops mounted on said drum adapted to push and rotate said reservoir, said reservoir being free to rotate at a velocity other than that of the drum when no longer pushed by said stops, a plurality of feeding orifices incorporated in the 60 lower portion of said reservoir for feeding ink, and a distributing element for supplying said ink to a pad of said mimeograph machine for uniformly inking a stencil mounted on said machine.

65 70 75 2. An inking device for mimeograph machines comprising a pendulous ink reservoir suspended from the axle of the drum of a mimeograph machine, stops mounted on said drum adapted to push and rotate said reservoir, said reservoir being free to rotate at a velocity other than that

of the drum when no longer pushed by said stops, a plurality of feeding orifices incorporated in the lower portion of said reservoir for feeding ink, and a distributing brush mounted on said reservoir and extending below said orifices for brushing the ink evenly over the inking region of said drum. 5

3. An inking device for mimeograph machines comprising a pendulous ink reservoir suspended from the axle of the drum of a mimeograph machine, stops mounted on said drum adapted to push and rotate said reservoir, said reservoir being free to rotate at a velocity other than that of the drum when no longer pushed by said stops, a plurality of capillary orifices incorporated in the 10 bottom of said reservoir for feeding ink, and distributing brushes mounted on each side of the reservoir and extending below the bottom thereof in meshing relation to brush the ink uniformly over the inking region of the mimeograph 15 drum.

4. An inking device for mimeograph machines comprising a pendulous ink reservoir adapted to be suspended from the axle of the drum of a mimeograph machine, stops mounted on said drum adapted to push and rotate said reservoir, said reservoir being free to rotate at a velocity other than that of the drum when no longer pushed by said stops, an air-tight inlet for introducing ink into said reservoir, a plurality of feeding orifices incorporated in the bottom of said reservoir for feeding ink, and a distributing brush mounted on said reservoir and extending below said orifices for brushing the ink evenly 20 over the inking region of said drum. 35

5. An inking device for mimeograph machines comprising a pendulous ink reservoir adapted to be suspended from the axle of the drum of a mimeograph machine, stops mounted on said drum adapted to push and rotate said reservoir, 40 said reservoir being free to rotate at a velocity other than that of the drum when no longer pushed by said stops, a manually operated air vent for permitting the entry of air into said reservoir, a plurality of feeding orifices incorporated 45 in the bottom of said reservoir for feeding ink, and a distributing brush mounted on said reservoir and extending below said orifices for brushing the ink evenly over the inking region 50 of said drum.

6. An inking device for mimeograph machines comprising a pendulous ink reservoir adapted to be suspended from the axle of the drum of a mimeograph machine, adjustable supports for suspending said reservoir on said axle, stops mounted on said drum adapted to push and rotate said reservoir, said reservoir being free to rotate at a velocity other than that of the drum when no longer pushed by said stops, a plurality of feeding orifices incorporated in the bottom 60 of said reservoir for feeding ink, and a distributing brush mounted on said reservoir and extending below said orifices for brushing the ink evenly over the inking region of said drum. 65

7. An inking device for mimeograph machines comprising a pendulous ink reservoir adapted to be suspended from the axle of the drum of a mimeograph machine, a pair of springs for maintaining said reservoir in a pre-determined axial position, stops mounted on said drum adapted 70 to push and rotate said reservoir, said reservoir being free to rotate at a velocity other than that of the drum when no longer pushed by said stops, a plurality of feeding orifices incorporated 75 in the bottom of said reservoir for feeding ink,

and a distributing brush mounted on said reservoir and extending below said orifices for brushing the ink evenly over the inking region of said drum.

- 5 8. An inking device for mimeograph machines comprising a pendulous ink reservoir adapted to be suspended from the axle of the drum of a mimeograph machine, stops mounted on said drum adapted to push and rotate said reservoir, 10 said reservoir being free to rotate at a velocity other than that of the drum when no longer pushed by said stops, a plurality of feeding orifices incorporated in the bottom of said reservoir for feeding ink, a pair of guards extending below the bottom of said reservoir and said orifices, and a distributing brush mounted on said reservoir and extending below said orifices for brushing the ink evenly over the inking region of 15 said drum.
- 10 9. The improvement in a mimeograph machine having a drum which comprises, in combination, an ink reservoir suspended within the drum, ink feeding means associated with the bottom of said reservoir, a pair of guards extending below the bottom of said reservoir, and a pair of stops within said drums to engage the guards of the ink reservoir when the drum is rotated in order to rotate the ink reservoir about the axis of the drum whereby the ink is automatically spread over the inner surface of said drum 20 during the operation of the machine.
- 15 10. The improvement in a mimeograph machine which comprises, in combination, a drum having an inking surface thereon, an ink reservoir suspended within the drum and a plurality of orifices incorporated in the bottom of said reservoir, a guard extending from each side of said reservoir to a region lower than the bottom thereof, and a pair of stops positioned at about the 25 extremities of said inking surface within said drum for engaging said guards, one of said stops being adapted to push and cause the rotation of the ink reservoir about the axis of the drum 30

and the other stop being adapted to engage the guard of the reservoir and limit rotation to the inking surface.

11. The improvement in a mimeograph machine having a drum which comprises, in combination, an ink reservoir revolvably suspended within the drum, ink feeding means associated with the bottom of said drum, a pair of guards extending below the bottom of said reservoir, stops mounted on said drum adapted to push and rotate said reservoir, said reservoir being free to rotate at a velocity other than that of the drum when no longer pushed by said stops, and a gutter extending inwardly at an angle to catch ink 10 splashed from said ink reservoir. 15

12. An inking device for mimeograph machines comprising a rotating drum having an inking surface thereon, a pendulous ink reservoir revolvably suspended from the axle of said drum, said reservoir having a plurality of orifices on 20 the bottom of said reservoir to permit a limited amount of ink therethrough until a vacuum is set up within said reservoir, means associated with said rotating drum for rotating said reservoir to permit air to be admitted through said 25 orifices when in an upturned position and dissipate said vacuum whereby another limited amount of ink may flow from said reservoir. 30

13. An inking device for mimeograph machines comprising a rotating drum having an inking 30 surface thereon, a pendulous ink reservoir revolvably suspended from the axle of said drum, said reservoir having a plurality of orifices on the bottom of said reservoir to permit a limited amount of ink therethrough until a vacuum is set 35 up within said reservoir, means associated with said rotating drum for rotating said reservoir to permit air to be admitted through said orifices when in an upturned position, and dissipate said vacuum whereby another limited amount of ink 40 may flow from said reservoir, and ink distributing means associated with said reservoir. 40

HUMBERTO L. BUENO.
